UNITED STATES PATENT OFFICE

WILLIAM H. MANNING, OF PONTIAC, MICHIGAN

RECIPROCATING ENGINE

Application filed August 2, 1929. Serial No. 382,968.

This invention relates to reciprocating engines, particularly engines of internal combustion type having multiple cylinders arranged in one or more rows longitudinal of the crank shaft.

Among the objects to be achieved are substantial freedom from vibration due to inertia torque and piston unbalance; even torque or even application of the turning efforts of the several pistons to the engine shaft; compactness in multiple cylinder engines having one or more straight rows of cylinders as compared with evenness of turning effort; equal apportionment of carbureted mixture to the several cylinders, and others inherent in the construction to be hereinafter described in detail.

The invention comprises an engine having an engine shaft provided with an odd number of throws, no two of which lie in the same plane, one or more pistons connected to each throw and one or more rows of cylinders in which the pistons reciprocate. It also comprises parts and details of construction as hereinafter described.

One embodiment of the invention is illustrated in the accompanying drawing wherein like parts are indicated by like reference characters.

In said drawing:

Fig. 1 is a perspective of a crank shaft and connected pistons made in accordance with the invention.

Fig. 2 is a section on the line 2—2 of Fig. 1 viewed from the rear toward the front.

Fig. 3 is a perspective of an engine block associated with intake and exhaust manifolds, and

Fig. 4 is a diagrammatic showing of a V—14 engine embodying the invention.

Fig. 3 depicts an automobile engine cylinder casting provided with seven cylinder bores in line, numbered 11, 12, 13, 14, 15, 16 and 17 from front to rear. These cylinder bores are illustrated as formed in a monobloc casting although they may be formed otherwise according to known practices. Intake manifold 20 extends fore and aft of the engine from a central riser disposed at one side of the block. Each end of the manifold 20

diverges into U-shaped branches 20f and 20r at front and rear respectively each branch terminating at opposite ends in delivery ports. The front end of branch 20f delivers to twin intake ports 21 and 22 in communication with cylinders 11 and 12, respectively, while the rear end of said branch delivers to twin intake ports 23 and 24 in communication with cylinders 13 and 14 respectively. The front end of the rear branch 20r delivers to intake port 25, in communication with cylinder 15 and its rear end delivers to twin ports 26 and 27, in communication with cylinders 16 and 17, respectively.

An exhaust manifold 30 communicating with exhaust pipe 30a extends also fore and aft of the cylinder casting in proximity to the intake manifold, and is adapted to heat the mixture in the intake riser and manifold according to usual practice. Branches extending inward toward the block from the exhaust manifold terminate, respectively, with exhaust port 31 for cylinder 11, twin exhaust ports 32 and 33 for cylinders 12 and 13; twin exhaust ports 34 and 35 for cylinders 14 and 15, and exhaust ports 36 and 37 for cylinders 16 and 17.

The engine shaft is indicated as an entirety by numeral 40. This shaft is illustrated as having four bearing journals numbered 44, 43, 42 and 41 from rear to front. At the rear end is attached the customary fly wheel indicated by dotted lines at 45 and at the front a timing gear 46 as usual. The shaft 40 has seven throws illustrated as eccentrics or crank pins carried between crank arms. These eccentrics or crank pins are numbered in the drawing from rear to front, 7, 6, 5, 4, 3, 2 and 1. The several eccentrics or pins are angularly displaced about the axis of the shaft in such manner that the radial planes connecting the eccentric or pin centers with the axis of the shaft will divide a circumference struck from said axis into seven preferably equal arcs ($360^\circ/7$).

Upon reference to Figs. 1 and 2 it will be seen, starting from eccentric or pin 1, that the eccentrics or pins are there shown spaced successively $360^\circ/7$ in the order 1, 7, 3, 5, 2, 6, 4 or the reverse,—i. e., pin 7 is angularly

spaced $51 \frac{3}{7}^\circ$ from 1; 3 is spaced $51 \frac{3}{7}^\circ$ from 7, and so on. With this arrangement it is apparent that the shaft may be easily constructed to be in static balance and that no two 5 longitudinally adjacent throws will pass in succession through the same radial plane including the shaft axis when the shaft is rotated.

In order to place the described shaft in 10 dynamic balance the mass of each of the intermediate short crank arms 46 connecting the eccentric pins to the shaft is extended slightly beyond the crank body represented by the circumference of the journals, the ex- 15 tended portions 46a serving as counterweights to counterbalance at least in part the opposite rotating masses. The long arms 47 may be curved and their masses disposed in known manner to participate in the dynamic 20 balancing.

The seven throw shaft illustrated is subject to a variable inertia couple of relatively small magnitude tending to rock the engine about a transverse axis. By placing small 25 counterweighting masses 48 and 49 at opposite sides of the shaft at the front and rear ends, respectively, the magnitude of this couple may be materially reduced. Viewing the crank shaft from the rear (the left of Fig. 1) 30 the center of the mass of counterweight 48 should be about 115° measured in a clockwise sense from the radial plane passing through the center of eccentric pin 1, and the center of mass of counterweight 49 should be 35 about 65° measured in the opposite sense from the same radial plane. The counterweights needed are small and may be forged integral with the shaft.

Fig. 1 shows the several pistons and connecting rods of a straight seven cylinder engine in their relation to the seven throw engine shaft. The pistons are indicated from rear to front end by reference characters 7p, 6p, 5p, 4p, 3p, 2p, 1p; the corresponding connecting rods are similarly identified by 7c, 6c, 5c, 4c, 3c, 2c, 1c.

Inspection of Fig. 1 and Fig. 2 will show that no two pistons and connecting rods reach either end of their several reciprocating 50 movements at the same time. Computation of the forces developed in a running engine of this construction indicate that the pistons and connecting rods exert substantially no unbalanced inertia torque tending to rock the engine about a longitudinal axis and no unbalanced primary or secondary free inertia forces tending to oscillate or vibrate the engine in planes parallel with the longitudinal axis. The inertia couple referred to tending 55 to rock the engine about a transverse axis may be overcome in part by said two light counterweights 48 and 49 (in an engine having a crankshaft $26\frac{1}{8}$ " long, $2\frac{7}{8}$ " bore and 4" stroke these counterweights are about 4.6 60 ounces in weight). If any objectionable vi-

brations due to said couple should occur they may be insulated from the chassis frame by known types of engine insulating mounts. The lightness and stiffness of the shaft gives it a natural frequency of torsional vibration so high that its period of objectionable resonance with respect to the frequency of the piston thrusts will be above the driving range of the engine. The turning efforts of the 70 pistons due to gas pressure will be so evenly distributed as to assure smoothness of power delivery. The crank shaft may be easily manufactured by forging a flat blank and giving maximum twists of approximately 75 26°.

In a four stroke cycle, "straight" seven cylinder engine having the eccentric pins of the shaft disposed as described the firing order is 1, 3, 2, 4, 7, 5, 6, if the crank shaft rotates counterclockwise viewed from rear to front. Reference to Fig. 3 shows that manifolding for this arrangement and firing order is advantageous, because no two cylinders draw combustible mixture from the same delivery port or valve pocket or same portion of the manifold adjacent the same delivery port in succession. For example, cylinder 11 draws from twin port 21 at the front end of the forward branch of manifold 20; the next cylinder to fire, cylinder 13, draws from twin port 23 at the rear end of said forward branch; the next cylinder to fire is cylinder 12, which draws from twin port 22 at the front end of the forward manifold branch, and the cylinder 14, firing next, draws from port 24 at the back end; and so it will be seen the remaining cylinders firing in succession draw mixture alternately from the rear and front ends of the rear branch of the manifold. There will be, accordingly, no impoverishment of fuel in any one cylinder due to the fact that the cylinder which fired immediately preceding took its charge from the same portion of the manifold.

A seven cylinder engine utilizing the described seven throw engine shaft is well adapted to operate as a two stroke cycle engine, giving seven turning impulses during each revolution. The firing order for a counterclockwise running two stroke cycle engine viewed from rear to front would be 1, 7, 3, 5, 2, 6, 4.

Crank shafts of the type illustrated having an odd number of throws no two of which lie in a common plane are also well adapted for engines having a plurality of rows of cylinders arranged in planes radiating from the crank shaft axis. The cylinders shown in Fig. 3 for example may be duplicated, one row being separated angularly from the other 102 $6/7$ ° as indicated by the angle γ_{ca} in Fig. 2 for an engine operating on the four stroke cycle in case even firing intervals are desired. The connecting rods of cylinders whose axes are on the same transverse plane would be 120 125 130

connected to the same crank pin or eccentric as is usual in V-engines.

As required by the statutes, I have explained the principle of my invention and have specifically described and illustrated one preferred embodiment thereof. I do not, however, intend to be limited in patent protection to the precise form of the exemplary embodiment disclosed, but refer to the claims 10 as defining the scope thereof.

I claim:

1. A reciprocating engine provided with cylinders, pistons and a crank shaft having seven throws no two of which lie in the same 15 radial plane, said throws being angularly disposed from one end to the other of the shaft in such order that if the shaft be rotated the throws will pass through a radial plane including the shaft axis in the order 1, 7, 3, 5, 2, 20 6, 4, or the reverse according to the sense of rotation.

2. A four-stroke cycle internal combustion engine having seven cylinders arranged in tandem and suitable inlet and outlet ports; 25 a piston in each cylinder; an engine shaft having seven throws no two of which lie in the same radial plane, and angularly disposed from one end to the other of the shaft in such order that if the shaft be rotated the 30 throws will pass through a radial plane including the shaft axis in the order 1, 7, 3, 5, 2, 6, 4 or the reverse, said throws reaching firing position in the order 1, 3, 2, 4, 7, 5, 6 or the reverse, in accordance with the sense of rotation; rods connecting the several pistons with the several throws; means for conducting exhaust gases from the outlet ports; an intake manifold communicating with all cylinder inlet ports by delivery ports so disposed that 40 no two cylinders firing in succession draw mixture from the intake manifold adjacent the same delivery port.

3. A four stroke cycle internal combustion engine having seven cylinders arranged in 45 tandem and suitable inlet and outlet ports, a piston in each cylinder and suitable connecting rods, an engine shaft having seven throws angularly disposed from one end to the other in such order that if the shaft be rotated the 50 throws will pass through a radial plane including the shaft axis in the order 1, 7, 3, 5, 2, 6, 4, or the reverse, according to the sense of rotation, reaching firing position in the order 1, 3, 2, 4, 7, 5, 6, or the reverse; rods connecting 55 the several pistons with the several throws; an intake manifold having four delivery ports, three pairs of adjacent cylinders having their inlet ports twinned, and communicating each with a single delivery port of the 60 manifold, and one cylinder having an individual inlet communicating solely with the remaining delivery port in the manifold; the arrangement providing that no two cylinders firing in succession draw mixture from the 65 same delivery port of the manifold.

4. A combination as defined in claim 3 in which the intake manifold has a main section extending fore and aft of the engine on opposite sides of a central riser, each end of said main section connecting with U-shaped 70 branches, each end of one branch delivering to twin cylinder inlets; one end of the other branch delivering to twin inlets and the other end of the last named branch delivering to an individual cylinder inlet. 75

5. An internal combustion engine having an odd number of cylinders, pistons, and connecting rods arranged in tandem, a crank-shaft having a corresponding odd number of throws, no two of which are disposed in the 80 same radial plane, the relative angular arrangement of the throws being such that no two throws that are longitudinally adjacent are in angularly adjacent planes. 85

6. An internal combustion engine having 85 suitable inlet and outlet ports, pistons, connecting rods and balanced crankshaft, said crankshaft having seven throws no two of which lie in the same radial plane, said throws being angularly disposed from one 90 end to the other of the shaft in such order that if the shaft be rotated no two longitudinally adjacent throws will pass through a radial plane including the shaft axis in succession, means for conducting combustible 95 mixture to the inlet ports, said means having delivery ports arranged with respect to the inlet ports so that no two cylinders firing in succession draw mixture from the manifold adjacent the same delivery port. 100

In testimony whereof I affix my signature.
